UNITED STATES PATENT OFFICE.

FRANK E. ELMER AND BOY W. ROBERTS, OF TOLEDO, OHIO.

HINGE CONSTRUCTION.

Application filed May 5, 1925. Serial No. 28,089.

This invention relates to hinge constructions and has for one of its objects to provide a hinge which will be simple in construction, comparatively inexpensive to manufacture and more efficient in use than those which have been heretofore proposed.

A further object of the invention is to provide a device of the class described for pivotally connecting together the abutting ends of adjacent sections of a pole, bar or the like, such for example, as poles of collapsible tent frames, clothes racks, quilting frames, etc., and which may be efficiently locked to provide an exceptionally rigid joint.

With the above and other objects in view, which will appear as the description proceeds, the invention consists in the novel details of construction and combinations of parts more fully hereinafter described and particularly pointed out in the appended claims.

Referring to the accompanying drawings forming a part of this specification in which like reference characters designate like parts in all the views;

Fig. 1 is a side elevational view of a hinge constructed in accordance with the present invention, as applied to a tent pole for example, the parts being shown in their closed or locked positions;

Fig. 2 is a front elevational view of the parts shown in Fig. 1;

Fig. 3 is a central vertical sectional view of the parts shown in Figs. 1 and 2, the hinge, however, being shown open or broken; and,

Fig. 4 is a sectional plan view of the parts as shown in Fig. 2.

The reference characters A, B represent respectively, two sections of a pole, rod or the like, such for example as a tent pole, the ends of which it is desired to pivotally connect together so as to abut in axial alignment as shown in Fig. 1. The hinge constituting the invention comprises a member 5 which may be stamped or suitably formed from sheet metal and which is provided with a portion 6 adapted to substantially encircle or surround the end of the pole section A as clearly indicated in the drawings. The said member 5 may be secured to the pole section A by means of suitable screws or other fastening devices 7, passing through the portion 6, substantially as shown in Figs. 2 and 3.

The said member 5 is further provided with the somewhat enlarged portion 8, forming a three sided socket adapted to receive the end of the pole section B, when parts are in the closed positions, shown in Figs. 1 and 2.

The side walls 9 of the portion 8 are provided with the extended ears 10 to which are pivotally secured as by the rod or bolt 11, the companion ears 12 of the hinge member 13 which embraces the end of the pole section B and which is secured thereto by the screws or other fastenings 14. The parts are so designed and constructed that when the ends of the sections A and B, abut as shown in Figs. 1 and 2, that the member 13 will be snugly received within the socket portion 8 of the member 5 and will be firmly supported therein by the three walls of the said socket member, that will be readily understood.

In order to efficiently lock the parts in the positions shown in Figs. 1 and 2, we have provided a simple locking mechanism comprising a substantially U-shaped strap member 15 which is also pivotally mounted on the rod or bolt 11 and which is provided with a suitable operating handle 16, as clearly shown in the drawings. The said strap member 15, pivotally carries the inverted substantially U-shaped bail 17, one portion 18 of which is adapted to be received in a pair of notches or recesses 19 which are provided in extensions 20 of the side walls 9 of the socket portion 8. The rear edges 21 of the recesses 19 are preferably vertical, as shown in Figs. 1 and 3, while the front edges 22 of the said recesses are preferably inclined somewhat so that when the portions 18 of the bail 17 enter the said recesses, a wedging or cam action will be had which will force the said portion 18 toward the end of pole section B, bringing it into engagement with the ears 23 of the hinge member 13 to rigidly lock the parts in their extended positions. It will be noted from Fig. 1, wherein the locking mechanism is shown in two positions, broken and full lines, respectively, that as the handle 16 is moved from the broken line position to the full line position that the pivot point 25 of the bail 17 is moved from one side of the center of the pivot rod or bolt 11 to the other side of the said center, thereby affording an automatic and positive assurance against the unintentional breaking of the

hinge, due to the locking mechanism being accidentally moved from its full line position to its broken line position shown in Fig. 1.

5 It is thought that the mode of operation of the hinge will be clear from the foregoing and it will, therefore, not be described in further detail.

While one form of the invention has been 10 illustrated and described, it is obvious that those skilled in the art may vary the details of construction as well as the precise arrangement of parts without departing from the spirit of the invention and therefore, it is not wished to be limited to the above disclosure except as may be required by the claims.

What is claimed is:

1. In a hinge construction of the class described, a pair of pivotally connected hinge members, one of which is adapted to be bodily received within the other in one position of the hinge and the other of which is adapted to receive said first named member, 25 one of said members being provided with a recess having an inclined face; and means carried by said members adapted to enter said recess and to be forced by said inclined face into engagement with the other member 30 and to positively lock said members in such position.

2. In a hinge construction of the class described, a pair of hinge members, one of which is provided with a pair of recesses; a 35 pivotal connection between said members; a U-shaped strap member pivotally carried by said connection; and a bail pivotally carried by said strap member, having a portion adapted to enter said recesses to prevent 40 relative movement of said hinge members.

3. In a hinge construction of the class described, a pair of hinge members, one of

which is provided with a plurality of recesses having inclined edges; a pivotal connection between said members; locking means 45 including a bail having a portion adapted to enter recesses and to engage said inclined edges to clampingly prevent relative movement of said members; and means pivotally carried by said connection and pivotally connected to said bail for moving the latter to and from locking position.

4. In a hinge construction of the class described, a pair of hinge members, each provided with a pair of extending ears, and 55 with a portion adapted to embrace and be secured to a pole section, one of said members being also provided with a pair of extensions having recesses therein, said recesses each having an inclined edge; means 60 pivotally connecting the ears of said members; a U-shaped strap member pivotally carried by said connection; an operating handle carried by said strap member; and a bail pivotally carried by said strap member, having a portion adapted to enter said recesses and to engage said inclined edges, to prevent 65 relative movement of said hinge members.

5. The combination with a pair of pole sections, the ends of which are adapted to 70 abut, of a hinge comprising a pair of members having a non-slidable pivotal connection between them, one member embracing and secured to each section, one of said members being formed to receive the other member; and means pivotally carried by said 75 pivotal connection adapted through pivotal movement on said connection to directly prevent relative pivotal movement of said hinge members.

In testimony whereof we affix our signatures.

FRANK E. ELMER.
ROY W. ROBERTS.
